UNITED STATES PATENT OFFICE.

ROBERT S. BOWEN, OF BOSTON, MASSACHUSETTS.

DESIGN FOR A PIANO-PLATE.

SPECIFICATION forming part of Design No. 27,763, dated October 19, 1897.

Application filed September 10, 1897. Serial No. 651,255. Term of patent 14 years.

To all whom it may concern:

Be it known that I, ROBERT S. BOWEN, a citizen of the United States, residing at Boston, in the county of Suffolk and State of Massachusetts, have invented and produced a new and original Design for Piano-Plates, of which the following is a specification, reference being had therein to the accompanying drawings.

10 In the drawings, Figure 1 is a face view of a piano-plate embodying my design, and Fig. 2 is a cross-section of the plate on the line 2 2 of Fig. 1.

In contour the plate bears some resemblance 15 to the profile of a Corinthian helmet, the essential features of its outline comprising the straight front line A, the connected lines C D E, extending rearward at different inclinations or angles to one another from or adjacent to one end of the front line A, the straight line F, extending at or substantially at right

angles rearward from the other end of said front line, and the long compound curved line G, extending from the rear end of line A around the rear portion of the plate. 25

The central portion of the plate is crossed at different angles by the struts or ribs H H, thus producing a barred effect. The surfaces I K in the front portion of the plate stand in an angular position with reference to each other, the surfaces at I standing in a decidedly oblique position with reference to the front line A. 30

I claim as my invention—

The design for a piano-plate substantially 35 as shown and described.

In testimony whereof I affix my signature in presence of two witnesses.

ROBERT S. BOWEN.
